UNITED STATES PATENT OFFICE.

REUBEN C. BAKER, OF COALINGA, CALIFORNIA, ASSIGNOR TO BAKER CASING SHOE COMPANY, OF COALINGA, CALIFORNIA, A CORPORATION OF CALIFORNIA.

CASING-PLUG.

1,392,619.

Specification of Letters Patent.

Patented Oct. 4, 1921.

Application filed September 29, 1919. Serial No. 327,281.

To all whom it may concern:

Be it known that I, REUBEN C. BAKER, a citizen of the United States, residing at Coalinga, in the county of Fresno and State 5 of California, have invented a new and useful Improvement in Casing-Plugs, of which the following is a specification.

This invention relates to an appliance for well casings and particularly pertains to a 10 plug for the lower ends thereof.

It often becomes necessary to plug the lower ends of a well casing and permanently seal it to prevent an upward flow of liquid therethrough. It is the principal object of 15 the present invention to provide a mechanical plug which may be easily lowered through the lower end of a well casing and thereafter wedged into the casing, and thereby exclude water and other foreign 20 matter from the lower end of the well casing.

The present invention contemplates the use of a torpedo-shaped member carrying a packing gasket, said member being easily 25 lowered into a well casing and manipulated so that the gasket will thoroughly pack around the body of the member and seal it, the torpedo member being further provided with means for permitting circulation of 30 water or other fluid therethrough while the lowering operation is taking place.

The invention is illustrated by way of example in the accompanying drawings, in which—

35 Figure 1 is a fragmentary view in vertical section and elevation, showing the casing plug while being lowered into a well.

Fig. 2 is a view in section elevation showing the casing plug after it has been lowered 40 to its extreme position and is ready to seal the well casing.

Fig. 3 is a view in vertical section and elevation showing the casing plug in its final permanent position.

45 Fig. 4 is a view in vertical section through the casing plug, more clearly disclosing its construction.

50 Fig. 5 is a view in transverse section through the body member as seen on the line 5—5 of Fig. 4.

Fig. 6 is a fragmentary view in elevation illustrating the manner in which the gasket seals the lower end of the casing.

55 In the drawings, 10 indicates a well casing extending into a shaft 11. The lower

end of this shaft is preferably filled with a mass of concrete 12 when it is desired to seal the end of the casing. This sealing operation is produced by the mass of plastic material 12 and a casing plug 13 with which 60 the present invention is particularly concerned.

The casing plug is formed with a body member 14 which has an inverted frustoconical portion 15 at its lower end and a 65 cylindrical portion 16 thereabove. The cylindrical portion is formed with an upper head 17, through which a threaded central opening 18 is formed and a plurality of by-pass openings 19. A bushing 20 is 70 mounted within the threaded opening 18 and is also secured to a hemispherical cap 21. This cap is adapted to lie flush upon the head 17 and has a plurality of outlet 75 openings 22 which will permit a circulation of fluid through the cap and the body member 14.

Securely held between the gap 21 and the body member is a canvas packing gasket 23. This gasket is formed by a circular piece 80 of canvas of such a dimension as to provide a wide marginal extension as particularly shown in Fig. 4 of the drawings. By means of this annular extension upon the gasket, it is possible to form a satisfactory seal between the body member 14 of the plug and the sidewall of the casing, at the same time wiping the sidewalls as the plug is passed to the lower end of the casing, and thereafter drawing the member into close engagement with the sidewalls without permitting an objectionable amount of plastic 85 material to enter the casing.

Extending downwardly through the member 20 and the cap 21 is an operating rod 95 24, by which the plug is forced to its lowermost position and afterward set in its permanent position. The upper end of this rod is formed with an eye 25 to which a string of tools or other suspending members may be secured. The lower end of the rod is permanently attached to a conical valve member 26. The outer contour of this member agrees with the outer surface of the body portion 15 and forms a complete tapered nose in combination therewith. A spring 27 is mounted around the rod 24 and acts between a collar 28 upon the rod and a spider 29 passed across the lower mouth 100 of the body portion 15. This spring acts in 105 combination with the valve member 26 to hold the valve member 26 in its lower position.

expansion to hold the member 26 against the body portion 15, under normal conditions. However, when the plug is being forced downwardly through the casing the point 26 5 will be moved to the position indicated in Fig. 1, so that any liquid or fluid within the casing may have free circulation through the plug and will not retard the downward travel of the plug member.

10 Attention is further directed to the fact that the cylindrical body portion 16 and the base of the frusto-conical body portion 15 are not of the same diameter but the cylindrical portion is somewhat reduced in 15 diameter. This is done so that clearance will be provided for the gasket 23 when it is folded downwardly and also a shoulder 30 provided to wedge the gasket in position within the casing and to insure that a tight 20 seal is produced.

In the operation of the present invention the plug is assembled as is particularly shown in Fig. 4 and when not in use the gasket 23 will extend outwardly in a single 25 plane as indicated by dotted lines in that figure. When the plug is to be used it is forced downwardly by the rod 25. This will cause the gasket to fold back over the cap 21 and wipe the side-walls of the casing 30 while being moved in the direction of the arrow —a— as indicated in Fig. 1. The downward force upon the rod 24 will overcome the lifting section of the spring 27 and will move the point 26 away from the body 35 position of the plug to form a circulating opening 32 for the purpose previously explained. The downward travel of the plug is continued until the body portion and gasket are completely passed through the 40 lower end of the casing and forced into a body of plastic material, such as concrete which was poured down the casing before the entrance of the plug. After the gasket has cleared the lower end of the casing the 45 plug may then be drawn in the direction of the arrow —b— as shown in Fig. 2 and the gasket turned downwardly and caused to lie around the cylindrical portion 16 of the body gasket, as more clearly shown in 50 Fig. 2. As the body member is drawn upwardly the gasket will pass around the cylindrical portion 16 and extend downwardly and outwardly over the shoulder 30. The thickness of the gasket and the dimensions 55 of the body member at the shoulder are such that a wedging action will be produced and a tight seal made. The rod 24 may then be disconnected from its fastening and the concrete caused to flow in around the plug 60 and hold it in its wedged position. When pressure is released upon the rod 24 the spring 27 will, of course, expand and draw the member 26 into a closed position so that the liquid or fluid within the well shaft 65 will not pass upwardly into the casing. The

cap member 26 will be held in closed position when the concrete sets, as will be understood.

It will thus be seen that by use of the device here disclosed the well casing may 70 be quickly and completely plugged, at the same time wiping the casing clean of cement or other foreign material and sealing the casing so that no such material or liquid or gas may flow into the casing after the cement 75 has set.

It will be evident from the foregoing description that various changes might be made in the general construction and arrangements of parts without departing from 80 the spirit of the present invention, as claimed.

Having thus described my invention, what I claim and desire to secure by Letters Patent is:—

1. A casing plug having a body portion formed with a frusto-conical nose, a cylindrical base of a reduced diameter forming a shoulder, a circular flexible packing gasket secured to overhang the base portion, means 90 from which the structure depends, and a movable nose cap carried by said means.

2. A plug for well casings including a body having a conical lower part and a cylindrical upper part the latter of less diameter than the portion of greatest diameter of the conical part and having a circular shoulder at the base of the cylindrical part, a top wall extending across the upper part and formed with a central threaded aperture and a series of by-pass openings, a bushing threaded in said aperture, a cup-like flexible gasket seated at its end wall on the top wall of the upper part and formed to surround the cylindrical part, a cap having a bottom seated on the end wall of the gasket and threaded on the bushing, the cap bottom having openings which register with the by-pass openings of the body, said gasket 100 having its free edge formed to engage over 105 the shoulder, lowering means for the plug, and means to allow circulation of fluid through the body upon downward movement of the plug and for preventing circulation when the plug is in operative position. 110

3. A plug for well casings including a body having a conical lower part and a cylindrical upper part, the latter of less diameter than the portion of greatest diameter of the conical part and having a circular shoulder at the base of the cylindrical part, a top wall extending across the upper part and formed with by-pass-openings, a cup-like flexible gasket seated at its end wall on the top wall of the upper part, a cap 120 seated on the end wall of the gasket and secured to the body and having openings to register with the by-pass openings, the gasket having its free edge engageable over 125 the shoulder, lowering means, and means 130

to allow circulation of fluid through the body upon down movement of the plug and to shut-off circulation when the plug is in operative position.

5. 4. A plug for well casings including a body having an upper reduced cylindrical part forming a shoulder, a gasket on said part having a skirt received in the reduced part and of a length to overhang the shoulder and to cause flaring of the skirt against the lower edge of the well casing, and lowering means for the plug.
- 10 5. A plug for well casings including a body, a gasket on the body having a skirt formed to have its free edge lie between the body ends and to engage the bottom end edge of a well casing, and means to secure the gasket to the body.
- 15 6. A plug for well casings including a body, a gasket on the body having a skirt formed to have its free edge lie between the body ends and to engage the bottom end edge of a well casing, said body having a top on which the gasket seats, a cap seated on top of the gasket, the body top and cap 25 having aligned by-pass openings, means to secure the cap to the body, means to lower the plug, and means to admit fluid circulation through the openings during down movement of the parts and for preventing 30 circulation when the plug is in operative position.

In testimony whereof I have hereunto set my hand in the presence of two subscribing witnesses.
